APPARATUS FOR ESCAPE FROM SUB-MERGED VESSELS

Joseph Robert Hartnett, Gary, Ind.

Application May 19, 1943, Serial No. 487,648

9 Claims. (Cl. 114—16.7)

The present invention relates to an apparatus for rescuing persons imprisoned in a sunken vessel or more particularly from a vessel of the submarine type, which has been disabled in such a manner, that it is impossible for it to rise to the surface of the sea, and that accordingly the imprisoned persons cannot be rescued, in which case they are left to die, as has already happened on many occasions.

With the knowledge that all submarines have what is called an air-tight or water-tight compartment, it is believed possible to furnish such compartment with a continuous supply of air for the men in the sunken submarine with the machine herein shown. It is possible to also release from the submarine each and every man in his turn and put him outside of the submarine to float to the top and save his life. If desired a man can be sent to the top and then returned to the inside of the sunken submarine without letting in one drop of water. Consider what this will mean to the Navy. If for instance one of the submarines is lying on the bottom of the ocean, then it would be possible to send a man up to the surface of the water as a lookout for enemy or friendly vessels and avoiding the necessity of bringing the submarine to the surface.

The main purpose of this machine however, is to save lives, therefore that particular phase will be first considered.

The preferred embodiment of my invention is illustrated in the drawings, and

Figure 1 shows an end view of a submerged submarine equipped with my life saving apparatus in action, that is to say, an escape tank has been released therefrom and risen to the surface of the sea.

Figure 2 is a horizontal partial section taken about midship of the vessel with the escape apparatus installed and ready for action.

Figure 3 is a vertical axial section of the apparatus taken along line 3—3 of Figure 2.

Figure 4 is a vertical transverse section along the line 4—4 of Figure 3, and

Figure 5 is a vertical transverse section of the vessel taken just in front of the escape apparatus.

Like numerals indicate the same parts in the different views.

Reference numeral 10 indicates the hull of a vessel, in this case a submarine, with a conning tower 11 and periscope 12 see particularly Figure 1 and in a suitable position a particular compartment has been set aside for the escape apparatus, said compartment or chamber 13 see Figures 2 and 5 is confined between the deck 14 and floor

15 and bulkheads 16 and to which entrance may be gained by a door 17. On the floor 15, and midway between the two sides of the vessel the escape apparatus, denoted in general by numeral 19 is mounted within a guide rail 20 on a ball race or circular track 20a so as to be turned thereon between the sides of the ship.

The apparatus consists of a cylindrical tube 21 of sufficient inside dimensions to conveniently house a man. This tube is secured at one end on a revolving base 22 and supported at the other end to a box or pocket 35 by a connection or closure 23 similar to a fire hose connection. It is necessary to have this type of revolving base 15 for the reason that the sunken ships or submarines come to rest on the bottom of the ocean in different positions. It may be resting on either one side or the other side or upright in its natural position. In any case the apparatus may be revolved on its track 20 to whatever side is clear of the ocean bottom. There is for this reason a box or pocket 35 for the connection 23 for the tube 21 on both sides of the ship so that the apparatus will operate at any angle.

25 The tube 21 and the plunger 24 therein are the most important parts of the whole apparatus see Figure 3. It consists of three parts having an upwardly open space which may be called a tub or cradle 24a, a front end 25 and a rear end 26. Of these the front portion 25 is composed of alternating steel rings 25a and rubber gaskets 25b held together and to the middle portion 24 of the plunger by a hollow rod 27. The rear end portion 26 of the plunger is similarly composed of alternating steel rings 26a, rubber gaskets 26b and a hollow tie rod 28. This plunger 24 is similar to that used in water pumps. It differs only in that it has a tub 24a in between the forward plunger portion 25 and rear plunger portion 26. This plunger 24 slides along the axis of the tube 21. A man enters the tube at an opening 29 over which a cover 30 is secured on the tube to close the entrance 29 to the cradle 24a into which the man enters whereupon the cover is put back in place, so as to close the opening 29. The man is now ready to enter the water.

40 The plunger 24 may be sent forward in any number of ways, preferably, as here shown, by 50 the gear and crank method as at 31, as other means of pushing the plunger may fail mechanically. As the plunger is pushed forward through the opening in the side of the ship, the rear plunger portion moves forward taking the place 45 of the forward portion to stop the entrance of 55 the forward portion to stop the entrance of

water. The plunger 24 with the cradle 24a is now outside of the ship, Figure 1, and the minute the water enters the tube, the man in his Mundson or Davis lung is lifted out and into the ocean. Thereupon the plunger 21 is brought back into the ship. The cover 30 is removed to permit the second man to enter after the plunger has been retracted within the tube 21.

In front of the plunger 24 is to be seen a box-like-formation 35 for housing of an air-line life-buoy 36, which is kept inflated all the time for instant use. For this purpose an air line 37 is provided running through the front hollow rod 27, with a suitable packing at its rear end and through the rings 26a and 26b of the rear end of the plunger and on to a reel 50 which unwinds when the plunger and life-buoy are projected into the water to float up to the surface. This air line is attached to the life-buoy 36 immediately before the tube 19 is fastened to the side of the ship. A side opening 38, covered by a lid 39 is therefore provided on opposite sides of the ship. The lid is held in position by bolts 40 which can be quickly released from inside the vessel by a half turn, and the lid dropped off suspended on its chain 39a.

The member 36 when risen to the surface as shown in Figure 1 and staying near the tank 43 will act, in an emergency, to rescue a person coming out of the tank, in the event the rescuing should miscarry in any manner.

Another reel 52, Figures 3 and 4, is placed next to the first reel 50 and provided with a cable 42 which runs through the hollow tie-rod 28 and connects at 46 with a tank 43, which is housed in the tub or cradle 24a of the plunger in order to be returned from the surface, and generally floating close to the side of the life-buoy 36, see Figure 1. This tank or container 43 is only used for carrying a man to the surface of the sea, when the depth is very great and the consequent water pressure is too high for a man to withstand. The tank 43 is built like a spinning top, pointed at one end as at 46 where the cable 42 is attached. It has double walls as at 43a, filled with compressed air to make it buoyant. The tank is preferably made of rubber or of light strong metal.

The tank 43 is provided with two doors 44 and 45. The door 44 on the upper side when the tank is in position, as seen in Figure 1 for a man to enter after passing through the opening 29 in the cylinder 19, and the door 45 for emerging at the forward end when the tub is released as seen in Figure 1. On ascending to the surface of the sea, the tank will turn so that its blunt end, with the end door 45 will be uppermost for an easy exit of the man imprisoned in the tank. Both doors are adapted for locking or opening from the inside as well as from the outside.

By means of the cable 42 the speed of ascent of the tub or tank 43 can be controlled. Said cable is covered with rubber to protect it from the effect of seawater, and it is of circular cross section and is easily attached or detached as at 46 to the pointed end of the tank 43. Packing as at 47 is provided around the cable to prevent water from entering the vessel, as is also the case with the air hose 37 at the rear end of the hollow rod 27, Figure 3.

Side by side on the revoluble base or pedestal 22 are mounted a pair of reels, one reel 52 for winding up the air line 37 by turning its crank handle 53, the other reel 50 with a crank handle 51 for the tank control cable 42.

The tube 21 of this apparatus 19 is mounted on

the base 22 so that it can be turned about a quarter turn around its axis in both directions from the center line of the vessel in order that entrance opening 29 may always be adjusted to be approximately horizontal in whatever "list" the vessel may have on the bottom of the sea. This for the purpose of facilitating the entry into the cradle 24a of the person to be rescued. As here shown this is accomplished by releasing the clamp handle 53, see Figure 3 of the clamping band 54 by means of which the tube 19 is secured on the base 22.

As shown in Figure 2, the entire apparatus may be swung out of firing position after releasing the front end connection 23 from the box or pocket 35 at the side of the ship. This is indicated by dot and dash lines in said figure, where the axis of the tube is pointed longitudinally of the vessel in order to take up less space and permit free passage fore and aft.

For the purpose of sending the plunger with a person lodged in the cradle 24a out of the vessel, after removing the cover 39 and also to send out the buoy 36, the ratchet gear 31, Figure 3, as already explained, is operated.

For rising from a great depth, the man to be rescued uses the tank 43 in order to be protected from the great pressure from the outside.

As the tank 43 proceeds to the surface, the cable 42 is let out from the reel. After the tank reaches the surface of the water the man inside releases the end door or water-tight cover 45 from the inside and gets out of the tank. Of course, there is no need for him to get out unless he can be picked up by a rescue party. It would be better to stay in the submarine until rescue comes with a continuous supply of fresh air and food supplies. But if a rescue party is on hand, he climbs out.

After the man has left the tank 43, the lid 44 can be closed automatically by means of a spring. As the tank is pulled down it is guided into place by means of the cone-shaped receiver end at 46 of the cradle through which the cable passes, bringing the point of the tank into the cone and forcing the tank to lie flat in the tub 24a, displacing what water would have been in the tub. When this is done, the plunger 24 is brought back, and the side door 44 of the escape tank 43 is opened for the next man to enter and start his trip to the surface.

It must be remembered at all times, regardless of the position of the plunger, that no more water comes in the tube 19 than that which is brought in by the tub which is very little and is prevented from spilling into the vessel by the closed lid 30. This water will stay at the same level all the time.

Although a preferred embodiment of the invention is set forth and described herein and illustrated on the accompanying drawings, it is not intended to limit the application thereto, except as required by the scope of the subjoined claims.

Having described the invention, what is claimed as new is:

1. Apparatus for escape from submerged vessel, comprising a base, a circular track on the vessel for said base, a tube carried on said base for horizontal revolving with said base and clamping means on the base permitting leveling adjustment of said tube around its axis, a box-like pocket formed on each side of the vessel, one end of said tube being closed and the other end opening into either one of the pockets on the

side of the vessel with an outlet into the sea and an easily detachable lid over said outlet; a plunger slideable in said tube and provided with a cradle portion for carrying an object, and propelling means for said plunger adapted for projecting said plunger through said outlet and depositing the object into the sea.

2. Apparatus for escape from submerged vessel, comprising a base, a circular track on the vessel for said base, a tube carried on said base for horizontal revolving with said base and clamping means on the base permitting leveling adjustment of said tube around its axis, one end of said tube being closed and the other end opening into a pocket on the side of the vessel with an outlet into the sea and an easily detachable lid over said outlet; a plunger slideable in said tube and provided with a cradle portion for carrying an object, and propelling means for said plunger adapted for projecting said plunger through said outlet and depositing the object into the sea; such pocket and lid being provided on opposite sides of the vessel and a water-tight releasable connection between said open end of the tube and said pocket.

3. Apparatus for escape from submerged vessel, comprising a base, a circular track on the vessel for said base, a tube carried on said base for horizontal revolving with said base and clamping means on the base permitting leveling adjustment of said tube around its axis, one end of said tube being closed and the other end opening into a pocket on the side of the vessel with an outlet into the sea and an easily detachable lid over said outlet; a plunger slideable in said tube and provided with a cradle portion for carrying an object, and propelling means for said plunger adapted for projecting said plunger through said outlet and depositing the object into the sea; such pocket and lid being provided on opposite sides of the vessel and a water-tight releasable connection between said open end of the tube and said pocket, a door on said tube providing entry for said object into the cradle portion of the plunger, said door being adapted for water-tight closing in order to prevent water from said cradle portion to splash out therefrom.

4. Apparatus for escape from submerged vessel, comprising a base, a circular track on the vessel for said base, a tube carried on said base for horizontal revolving with said base and clamping means on the base permitting leveling adjustment of said tube around its axis, one end of said tube being closed and the other end opening into a pocket on the side of the vessel with an outlet into the sea and an easily detachable lid over said outlet; a plunger slideable in said tube and provided with a cradle portion for carrying an object, and propelling means for said plunger adapted for projecting said plunger through said outlet and depositing the object into the sea; a buoy deposited in said pocket, a water insulated air line for said buoy running, end to end, through said plunger and to which said buoy is attached to obtain compressed air, a reel secured on said base permitting unwinding of said air line when said buoy floats out from the pocket, and also winding up of the air line for redepositing the buoy in said pocket.

5. Apparatus for escape from submerged vessel, comprising a base, a circular track on the vessel for said base, a tube carried on said base for horizontal revolving with said base and clamping means on the base permitting leveling adjustment of said tube around its axis, one end of said tube

being closed and the other end opening into a pocket on the side of the vessel with an outlet into the sea and an easily detachable lid over said outlet; a plunger slideable in said tube and provided with a cradle portion for carrying an object, and propelling means for said plunger adapted for projecting said plunger through said outlet and depositing the object into the sea; said object consisting of a tank of elongated shape with an interior space of a size to house a person and provided with a front end opening and a side opening for the entry and exit of such person, and water-tight covers for said openings.

6. Apparatus for escape from submerged vessel, comprising a base, a circular track on the vessel for said base, a tube carried on said base for horizontal revolving with said base and clamping means on the base permitting leveling adjustment of said tube around its axis, one end of said tube being closed and the other end opening into a pocket on the side of the vessel with an outlet into the sea and an easily detachable lid over said outlet; a plunger slideable in said tube and provided with a cradle portion for carrying an object, and propelling means for said plunger adapted for projecting said plunger through said outlet and depositing the object into the sea; said object consisting of a tank of elongated shape with an interior space of a size to house a person and provided with a front end opening and a side opening for the entry and exit of such person, and water-tight covers for said openings, said object having double walls filled with compressed air.

7. Apparatus for escape from submerged vessel, comprising a base, a circular track on the vessel for said base, a tube carried on said base for horizontal revolving with said base and clamping means on the base permitting leveling adjustment of said tube around its axis, one end of said tube being closed and the other end opening into a pocket on the side of the vessel with an outlet into the sea and an easily detachable lid over said outlet; a plunger slideable in said tube and provided with a cradle portion for carrying an object, and propelling means for said plunger adapted for projecting said plunger through said outlet and depositing the object into the sea; said object consisting of a tank of elongated shape with an interior space of a size to house a person and provided with a front end opening and a side opening for the entry and exit of such person, and water-tight covers for said openings, the rear end of said object being tapered to fit the correspondingly shaped rear end of said plunger, a control cable attached with one end to the tapered rear end of said object and housed centrally in the rear end of said plunger, a reel on said base for unwinding and winding of said controlling cable upon the running out of said object when the plunger is projected through said outlet, and said reel being also adapted for winding up the control cable when said plunger is retracted.

8. Apparatus for escape from submerged vessel, comprising a base, a circular track on the vessel for said base, a tube carried on said base for horizontal revolving with said base and clamping means on the base permitting leveling adjustment of said tube around its axis, one end of said tube being closed and the other end opening into a pocket on the side of the vessel with an outlet into the sea and an easily detachable lid over said outlet; a plunger slideable in said tube and provided with a cradle portion for carrying an object, and propelling means for said plunger adapted for

projecting said plunger through said outlet and depositing the object into the sea; such pocket and lid being provided on opposite sides of the vessel and a water-tight releasable connection between said open end of the tube and said pocket, a door on said tube providing entry for said object into the cradle portion of the plunger; said door being adapted for water-tight closing in order to prevent water from said cradle portion to spill into the vessel; a buoy deposited in said pocket, a water insulated air line for said buoy running, end to end, through said plunger and to which said buoy is attached to obtain compressed air, a reel secured on said base permitting unwinding of said air line when said buoy floats out from the pocket, and for winding up of the air line for redepositing the buoy in said pocket, said object having double walls filled with compressed air.

9. Apparatus for escape from submerged vessel, comprising a base, a circular track on the vessel for said base, a tube carried on said base for horizontal revolving with said base and clamping means on the base permitting leveling adjustment of said tube around its axis, one end of said tube being closed and the other end opening into a pocket on the side of the vessel with an outlet into the sea and an easily detachable lid over said outlet; a plunger slideable in said tube and provided with a cradle portion for carrying an object, and propelling means for said plunger

adapted for projecting said plunger through said outlet and depositing the object into the sea; such pocket and lid being provided on opposite sides of the vessel and a water-tight releasable connection between said open end of the tube and said pocket, a door on said tube providing entry for said object into the cradle portion of the plunger, said door being adapted for water-tight closing in order to prevent water from said cradle portion to spill into the vessel, a buoy deposited in said pocket, a water insulated air line for said buoy running, end to end, through said plunger and to which said buoy is attached to obtain compressed air, a reel secured on said base permitting unwinding of said air line when said buoy floats out from the pocket, and also winding up of the air line for redepositing the buoy in said pocket, said object having double walls filled with compressed air, the rear end of said object being tapered to fit the correspondingly shaped rear end of said plunger, a control cable attached with one end to the tapered rear end of said object and housed centrally in the rear end of said plunger, a reel on said base adapted for unwinding and winding of said controlling cable upon the running out with said object when the plunger is projected through said outlet, and said reel being also adapted for winding up the control cable when said plunger is retracted.

JOSEPH ROBERT HARTNETT.
